UNITED STATES PATENT OFFICE

2,422,055

GAITER

Max A. Varon, Chicago, Ill., and Carl S. Malone,
Owensboro, Ky.

Application April 20, 1945, Serial No. 589,316

1 Claim. (Cl. 36—2)

1

Our invention relates to footwear, and has for its principal object to provide a gaiter secured over the shoe; a gaiter which has integrally formed therewith a flared-out portion to be draped above the ankle of the foot of a wearer to form a horizontally projecting mud guard to prevent splashing of mud and slush, when worn in rainy and slushy weather, thus protecting fully the rear portion of the leg where most of the splashing should be intercepted which is caused by the impact of the heel with the pavement.

Another object of our invention is to provide a gaiter of the aforementioned character which is made of an inner section or quarter and an outer section or quarter interconnected by an arch locating portion, and which is provided with an opening to locate about the heel portion of a shoe and immediately above its top portion, an article which is of simple construction, practical and effective for wearing purposes, and which can be economically manufactured in quantity production.

Other features, objects and advantages inherent in our invention will become apparent from an examination of the accompanying drawings, having particular reference to the ensuing description, wherein like symbols are used to designate like parts, and in which;

Fig. 1 represents a perspective view of our invention as shown draped on the leg of a person wearing the same.

Fig. 2 is a side view showing the pattern relationship of one side of the gaiter comprising our invention prior to its being secured on the foot.

Fig. 3 is a cross-sectional view taken, substantially, on the line 3—3 of Figure 2.

Fig. 4 is a side view, similar to Figure 2, showing the opposite side of the gaiter construction preparatory to its being attached to the foot.

Fig. 5 is a plan view of our invention showing it spread open ready to receive the heel member of a shoe preparatory to securing the gaiter to the foot of the wearer.

Fig. 6 is a slightly modified form of our invention showing the interconnecting strap portion which locates below the arch of the shoe of a wearer, in this particular instance made as a separate element, and made of an elastic type of material for reasons which will be more clearly elucidated in the description.

Referring to the various views, it is to be noted that the leg of a wearer is, generally, designated 7, and the vamp of the shoe worn by the said wearer designated 8, the heel element being designated 9, while our invention, generally, is desig-

2

nated 10. Our invention is comprised of an inside quarter 12 and an outside quarter 12', both being symmetrical in configuration; each one being made up of a heel portion 11 configurative with the rear portion of a shoe and fitting closely the shape thereof. The said heel portion 11 merges with a downwardly extending portion 17 to form the arch locating and interconnecting strap, the said portion 11 being adjacent to the fly portion 15 which is a gored or angular extension. On the opposing side of the heel portion 11 is provided another angular or triangular portion 19 which merges with the intermediate arcuately shaped portion 22 in order to provide an extended arcuate portion 16 to permit forming the same into a horizontally extended mud guard or protector 24.

The heel portion edges are sewed at 13, and the extending gore-shaped portion 19 is sewed at 14, while the remaining portions are open with the exception of the portion 18 which is stitched together in order to form the bottom strap locating section when the portions 17 are joined together. To the front gored portion or fly 15, the snap fastener elements 21 are secured which cooperate with mating snap fastener elements 27 secured to the other quarter so that the front portions 15 may be brought into overlapping engagement, the snap fasteners 21 and 27 securing the lower part of the gaiter about the shoe, the locating strap formed of the portions 17 positioning itself at the proper point in the arch of the shoe; thus the upper portion 22 is left free, and being substantially larger in area permits the mud guard or protector portion 24 to be rolled in position as indicated in the view of Figure 1, extending a distance substantially back of the heel element 9 and the profile of the leg 7, thus preventing the splashing which occurs within the vicinity of the heel 9 from reaching the upper exposed portion of the leg 7 actually protecting the hose which covers that portion of the leg 7 which is above the mud guard portion 24.

It can be readily seen and understood how the mud guard 24 will intercept any of the splashing from the heel directed upwardly, and thus will protect the wearer from having the leg, or stocking, or clothing soiled by the splashing of mire, slush, etc.

The form shown in Figure 6 is, substantially, the same as the form shown in the remaining figures, with the exception that the portions 17 are omitted. In this instance the inside and outside quarters are provided with a straight portion at the bottom, and a separate element 23 forming

the locating strap for positioning below the arch which is, preferably, made of a suitable elastic material. The element 23 is stitched to the inside and outside quarters on the line 26. By virtue of this slightly modified form, the elasticity provided in the element 23 will cooperate more effectively with the binding or securing means 21 and 27 so that a more comfortable and snug fit may be obtained about the ankle and the instep of the foot.

The said construction being of the same pattern also permits the formation of a mud guard 24 to intercept the splashing of mud, rain and slush water, etc.

The entire structure has its free edges stitched as at 20 in order to form a finished edge to prevent unravelling of raw edges of material which would otherwise take place, if this were not resorted to.

The article is very simply attached, the heel 9 is inserted in the opening 25 the gaiter draped over the heel portion of the shoe carefully so that the portion 11 fits snugly at the back, while the strap element formed of the resilient material or of the portions 17, is located in suitable position below the arch of the shoe, after which the snap fastener elements 21 and 27 are brought into engagement so that the fly portion 15 will be superimposed over its mating fly portion on the other quarter of the gaiter, then the portion 22 is rolled in position to form the splash proof guard 24 heretofore mentioned.

We believe that we have herein described rather succinctly the construction, utility, and application of our invention, and inasmuch as the same is susceptible of modifications and improvements, we hereby reserve the right to all modifications and improvements coming within the scope and spirit of our invention, also those embraced in the embodiments of the accompanying drawings, as

well as those lying within the purview of the foregoing description.

Having thus described and revealed our invention, what we claim as novel and desire to secure by Letters Patent is:

5 A gaiter comprising, an outer quarter and an inner quarter, each of said quarters including a heel portion, a gored portion adjacent thereto, a depending strap portion contiguous with the bottom edge of the said quarter, a second gored portion adjacent the said strap portion, and an arcuate portion interconnecting the said gored portions, the edge of the said heel portion and the adjacent portion of the said first-mentioned gored portion being suitably stitched together, the free ends of the said strap portion also being stitched to form an arch locating strap and an opening adapted to receive the heel of a shoe, and concealed snap fastening means secured to the said second-mentioned gored portions adapted to removably retain them in overlapping relationship, the said arcuate portion being adapted to be formed into an annularly-flared mud guard or protector of substantially semi-circular cross-section extending outwardly and downwardly a substantial distance away from the said heel portion.

MAX A. VARON.
